UNITED STATES PATENT OFFICE.

WILLIAM FULTON WALKER, OF CHICAGO, ILLINOIS.

MAIL-BOX.

1,344,281.

Specification of Letters Patent. Patented June 22, 1920.

Application filed March 20, 1916. Serial No. 85,294.

To all whom it may concern:

Be it known that I, WILLIAM FULTON WALKER, a citizen of the United States, and resident of the city of Chicago, in the county of Cook and State of Illinois, have invented certain new and useful Improvements in Mail-Boxes, of which the following is a specification.

My invention relates to mail boxes. In 10 the adaptation thereof illustrated it has more particular reference to mail boxes for apartment buildings and the like situations.

In apartment buildings and the like where mail matter is delivered to the tenants there- 15 of by inserting the same in individual mail boxes assigned to the tenants respectively and usually located on the ground floor near the building entrance, much inconvenience to the postal authorities and to the tenants 20 has heretofore resulted from the insertion thereinto of circulars, booklets, etc., by unauthorized persons, such as house-to-house advertising distributers. The tenant not only seriously objects to having a great 25 variety of advertising matter thrust upon him in this manner, but the result frequently is that such mail boxes are so filled or "stuffed" with such unauthorized matter that the box is rendered incapable of receiving or of safely housing the mail proper. So far as I am aware, also, hitherto suggested mail boxes of this character have not been constructed to provide the desired security 30 against unlawful abstraction of their contents through the mail-receiving opening. The safe housing of the mail in these boxes is a matter of importance both to the Government and to the tenant; and the Government employees delivering mail to such 35 boxes are personally concerned in the security of such mail matter as in many cases of unlawful abstraction from such boxes suspicion has been unjustly directed toward such employees, and the Post Office Department is also often unjustly condemned on the same grounds.

The principal objects of the present invention are to overcome the above mentioned and other objections and disadvantages and 50 to overcome them by simple means, easy of operation. It is also an object to provide an indicator for mail matter authoritatively inserted in such box or boxes; also to provide a locked mail box which may be opened 55 without the use of a key by the person whose mail is contained therein, thereby rendering

the opening and closing of the box more convenient than where a portable key is employed, and also thus overcoming the disadvantages incident to the loss or misplace- 60 ment of such key; and, further, to provide simple and effective means for securing a name plate to the device. Other objects and advantages will appear hereinafter.

In the accompanying drawings, which 65 form a part of this specification, I have illustrated a preferred embodiment of these improvements. In these drawings Figure 1 is a rear view of a plurality of such mail boxes with the rear walls thereof removed;

Fig. 2 is a fragmentary front view showing principally the middle box of the three shown in Fig. 1;

Fig. 3 is a vertical section through one of the boxes as on the line 3-3 of Fig. 1 showing the indicator in its forward position;

Fig. 4 is a fragmentary section on the line 3-3 of Fig. 1 showing the indicator in retracted position; and

Fig. 5 is a horizontal section on the line 5-5 of Fig. 2.

A plurality of such mail boxes are usually formed as a single unit for economy in construction and space, and I have shown three thereof to illustrate the improvements set 85 forth. Each of the boxes A, B and C is provided with an opening 10 for the insertion of mail. A closure 11 hingedly mounted as at 12 is adapted to close or obstruct the opening 10, the closure being moved out of 90 obstructing position by mail matter when the same is inserted through the opening 10. Each closure, as 11, is independent of the other closures 11, as will be pointed out further hereinafter. A locking bar 13 is 95 hingedly mounted, as at 14, and in the specific arrangement shown is adapted to press against each of the closures 11, a spring, as 15, on the hinge rod 15^b being adapted to maintain the locking rod 13 against the 100 closures 11, and thus maintain the closures 11 yieldingly in closing or obstructing position with respect to the openings 10. When mail is inserted through an opening 10 the closure 11 at that opening and the locking 105 bar 13 are moved inwardly on their respective pivots, against the resistance of the spring 15. An opening 16 in the partition walls, as 16^a, 16^b, provides clearance for the movement of the locking bar 13. A lock 110 17 secured to the front wall of the box and having a keyhole 18 leading thereto from

the front of the box has a bolt 19 adapted to engage the locking bar 13, as shown in Fig. 1, by which arrangement when the bolt 19 is in such locking position the locking bar 13 and all of the closures 11 are maintained against movement and it is impossible to insert mail through any of the openings 10.

The operation of the mail box or boxes 10 in this regard is to provide the postal authorities with a key adapted to be inserted in the keyhole 18 and to shift the bolt 19, such key being adapted to operate in all the locks of the same character in the boxes 15 which the carrier may find on his route. The carrier, on coming to the mail boxes, operates the lock 17 to release the locking bar 13, whereupon the individual closures are released and the carrier is enabled to insert 20 mail matter in any of the boxes having closures under the control of that lock. Having made his delivery he again locks the locking bar 13, and thus renders each individual box secure not only against the 25 insertion of unauthorized matter, but also, and importantly, against the abstraction of mail from the box through an opening or openings 10.

In the preferred use of such devices an 30 indicator is also provided for showing that authorized mail matter is within the box, such indicator avoiding the use of a glass window through which the contents of the box may be seen by the public. A preferred 35 form of such indicator is the gravity lever 20 pivoted as at 21 intermediate its ends, one end carrying an indicator proper 22 adapted to project through an opening 23 in the front wall of the box. A gravity 40 latch 24 pivoted as at 25 and having a weighted end 24^a has a shoulder 26 adapted to engage the extended end or catch 27 of the lever 20 whereby when the parts are in their relative positions as shown in Fig. 3 45 the indicator lever 20 is locked. The latch 24 carries a stud or projection 28 adapted to be engaged by an inclined surface on the tripping lug or projection 29 secured to the door 30 whereby when the door 30 is swung 50 outwardly on its hinges 31 the end of the latch 24 carrying the stud 28 will be depressed against the force of gravitation operating upon the end 24^a whereby the end 27 of the indicator rod 20 will come out of 55 engagement with the shoulder 26 and the indicator proper 22 will swing inward under the force of gravitation until the same is out of indicating position, as shown in Fig. 4. When the parts are in their relative 60 positions as shown in Fig. 4 and mail matter is inserted through the opening 10 (the locking bar 13 being unlocked) the closure 11 for that opening will engage the extension 20^a of the lever 20, moving the indicator proper 65 22 outward into indicating position where

it becomes latched and held by the latch member 24.

For locking the door 30 I provide a latch bolt 32 operated from the outside by a finger piece 33, the latch bolt being locked by a 70 permutation device 34. By means of a knob as 34^a the pointer 36 is moved over the dial and, when the proper "combination" has been made, the door is opened by rocking the finger piece 33. I have not illustrated 75 the details of the permutation lock as such locks are well known, and any suitable one may be employed. I am not aware, however, that such permutation locks have been applied to mail boxes heretofore and I consider the combination of such permutation lock with a mail box of the character described a valuable advance in the art in the convenience to the user by dispensing with 80 a key and in the great security which the 85 almost endless number of permutations affords.

Another feature of improvement is in means for securing a name plate to the device. In the preferred arrangement the 90 door 30 is provided with an opening 35 and a name plate 36 is exposed therethrough. A keeper bar or plate 37 pivoted as at 38 is adapted to maintain the name plate in its desired position, suitable means, such as the 95 overlapping beads 39 secured to the door 30 about the opening 35 being adapted to co-operate with the bar 37 in holding the name plate in place. The hinge lug 40 secured to the door has an upturned flange 41, and the 100 reduced end of the bar 37 interfits between the same and the door 30, thus locking the name plate securely in its desired position, and rendering it impossible to force the name plate into the box and thus gain access to the interior thereof. By merely swinging the holding plate or keeper 37 upward the name plate 36 is readily inserted or removed.

In order to give direction to mail matter 110 inserted through an opening 10 whereby it may be carried toward the rear of the box substantially uniformly and there become arranged more systematically, the box being thus adapted to contain more mail matter than where it is permitted to fall without such direction, I provide a deflector as 115 43 secured to the front wall of the box. Such deflector has the further advantage, in mail boxes which are not provided with a 120 locked closure, of preventing the abstraction of mail, by means of a wire inserted through the mail-receiving opening, as 10.

The preferred form of lock for the closures 11 and locking bar 13 is such that the 125 bolt 19 is retracted when the key in the hand of the mail carrier is merely pushed into the keyhole 18, and such that when the key is merely withdrawn the bolt 19 is forced by spring pressure into its locking position. 130

Locks operating on this principle are well known and no detailed description or illustration of the same is required. As the spring 15 automatically brings the locking bar 13 into position to be locked as soon as the mail matter has passed into the box, it is apparent that the operation of the mail carrier is merely to insert the key on making deliveries and to withdraw the same when he is through, the closures 11 thereupon automatically becoming locked.

While I have illustrated and described a preferred embodiment of these improvements various changes may be made in details of construction and arrangement of parts without departing from the spirit of this disclosure, and all such changes are contemplated by me as fall within the scope of the appended claims.

I claim:

1. The combination with a mail box having an opening in the front wall thereof to receive mail, of a spring-pressed movable closure for said opening, said closure being adapted to be moved when mail is inserted through said opening, a pendant oscillatory indicator within said box under the control of said closure, said indicator being in such relation to said closure as to be projected outward through a suitable opening in the front wall of the box against the action of gravitation when mail is inserted through said opening, said box having a movable door in the front wall of the box for gaining access to mail in said box, means for locking the indicator in its projected position, and means under the control of said door for releasing said indicator when the door is opened whereby the indicator may

move by gravitation into non-indicating position.

2. The combination with a mail box, of an indicator therein pivoted intermediate its ends, said box having a mail opening, a movable closure for said opening, means for locking and unlocking said closure, said closure being in operative connection with one end portion of said indicator to move the other end thereof against the force of gravitation into indicating position when mail is inserted through said opening, a latch adapted to hold said indicator in indicating position, a movable door for gaining access to mail in said box, said latch being under the control of said door whereby the latch is tripped to release said indicator when the door is opened, said indicator being adapted thereupon to move by gravitation into non-indicating position.

3. In combination, a mail box having an opening in a wall thereof for a name plate positioned in the inside of said box at said opening so as to be exposed therethrough, a swinging backing piece pivoted at one end and adapted to lie against such name plate to hold the same in position at said opening, said backing piece being coextensive with said opening so as to close said opening should such name plate be removed or be absent therefrom, and means for holding the free end of said backing piece whereby said backing piece is held in such opening closing position.
